COMBINED TOOTHBRUSH, TOOTH PASTE TUBE AND TUMBLER HOLDER

Marie C. Oland, Los Angeles, Calif.

Application April 18, 1958, Serial No. 50,512

Term of patent 3½ years

(Cl. D4—3)

Figure 1 is a perspective view of a combined toothbrush, tooth paste tube and tumbler holder, showing my new design, looking from the top and at one side and end thereof;

Figure 2 is another perspective view looking from the top and the other side and end;

I claim:
The ornamental design for a combined toothbrush, tooth paste tube and tumbler holder, as shown.
